UNITED STATES PATENT OFFICE.

JOSEPH J. ZETĀK, OF HOLLAND, TEXAS.

DESIGN FOR A RIDGE-CONDUIT.

49,247.

Specification for Design.

Patented June 20, 1916.

Application filed November 10, 1915. Serial No. 60,793. Term of patent 3½ years.

To all whom it may concern:

Be it known that I, JOSEPH J. ZETĀK, a citizen of the United States, residing at Holland, in the county of Bell and State of Texas, have invented a new, original, and ornamental Design for a Ridge-Conduit, of which the following is a specification, reference being had to the accompanying drawing, forming part thereof.

Figures 1 and 2 illustrate a ridge conduit showing my new design.

I claim:

The ornamental design for a ridge conduit as shown.

In witness whereof, I have hereunto subscribed my name this 5 day of November 1915.

JOE J. ZETĀK.
